UNITED STATES PATENT OFFICE.

FREDERICK W. MOORE, OF EAST ORANGE, NEW JERSEY.

PROCESS OF MAKING COVERING MATERIALS.

Application filed May 11, 1916. Serial No. 233,982.

To all whom it may concern:

Be it known that I, FREDERICK W. MOORE, a citizen of the United States, residing at East Orange, in the county of Essex and State of New Jersey, have invented a new and Improved Process of Making Covering Materials, of which the following is a specification.

My invention relates to a process of making covering materials by uniting to a fabric of intersticed or cellular construction, by means of a plastic coating body, a surface of leather, either of a single or a number of pieces or layers or a number of pieces, one overlapping another, and as illustrated in the accompanying drawings, in which—

Figure 1 is a view illustrating the manner of uniting several pieces of skin and of applying the fabric thereto in one way of utilizing the invention.

Figure 2 is a detail sectional view of a portion of the structure shown in Figure 1.

Figure 3 is a detail view illustrating one step in the process of forming my improved covering.

In carrying out my invention I apply to a hide or skin or portion thereof constituting a basic material 5, a plastic coating body 6 which has an affinity for and combines with leather and acts as a mordant in its soluble condition, filling the pores by penetration and creating a flexible film on cohesion therewith which adds to its substance, and while in an adhesive condition a textile fabric 7 is spread upon its surface, the fabric being of an intersticed or cellular construction preferably, and the leather and the cohesive body in solution are embedded and anchored into the mesh or interstices to fill the fabric, imparting thereto the body substance of the basic material, that is, the leather and the cohesive coating body which concretes, unites the material, and gives the consistency and character of the one to the other. The textile fabric thus becomes the integument of the leather or basic body and the leather a layer of body substance that imparts the leather utility and surface finish to the textile.

The leather or basic body may then be split as shown in Figure 3 to level the sheet by cutting the projections and the textile is thus given its complement of leather anchored and embedded in its mesh and forming a body substance which gives the textile

the consistency, characteristics and utility of the natural integument of a hide or skin and the thin leather the strength and consistency and utility of a heavier body or layer of leather.

In further carrying out my invention a great saving may be effected when the basic material 5 is composed of two or more sides or segments 8 of leather of uneven thickness of substance and irregularity of shape that are overlapped to distribute the substance so that a thin portion is made of more uniform substance with a thicker portion after it has been beveled or evened up by splitting or by shaving the ridges of the overlay. The surface area that is evened up by shaving the ridges of the overlapped portions to bevel the same is thus made more regular for the application of the textile.

If the mesh of the textile 7 is of design not sufficiently open or porous or too fine to permit the basic material 5 to impregnate the mesh sufficiently, the textile is forced open under tension by tentering out. The flexible coating material while in solution may be applied to the textile and thus applied to the leather, and the coating material will consequently be applied to the outer surface penetrating to the basic body, uniting with and forming a homogeneous connection between the basic material and the surface coating, the textile being thus interposed under tension, undesirable stretching is eliminated and confined air cells are avoided.

The surface or surfaces of the covering may be perforated or punched in such a way that the fibers of one impregnates the other and fills the same and the perforations so spaced are designed to imitate the animal hair pores such as appear in pig-skin, and coating or finishing applied to either the surface of the textile or the leather or basic material becomes substantially homogeneous with the body substance of the covering.

The porosity are the especial design of leather characteristics may and preferably will apply to the construction of the weave or the formation by embossing of the textile fabric when in plastic condition but the weave may also be of an ornate design to give the cloth appearance to the finish.

If the textile is formed to imitate the animal grains, embossing and also the coatings

may emphasize the effect and coating material suitable for a finish will make the effect more permanent in wear.

This permanency of design is increased by the splitting operation which cuts the projections formed by the textile in the leather by which the design of the textile is transferred to the leather surface so that structurally this surface is more suited for wear; having the embedded holding contact of the leather in the mesh of the textile, giving a wearing value to this very thin leather body. Unless the textile is united to the leather by cellular impregnation to substantially become an integument thereto, the textile acts simply as an apron or backing to distribute the substance to hold out the weak spots and extremities and in the splitting the knife follows the line of least resistance separates the textile at points of imperfect contact or wherever air is confined by such contact.

It should be noted that the joining of several hides, as hereinbefore described, into one long roll, will produce a strip without perceptible seams, this by reason of the fact that the edges are beveled and lapped so that the joint is perfectly smooth and without ridges, and the splitting makes a joining that shows no seam, especially when coating material is applied and the surface finished, and this is true whether or not the backing of textile be applied to such strip. By this process a roll comprising a number of hides or segments thereof of indefinite length may be cut for any purpose desired and without any attention being paid to the portions where the pieces are overlapped and united and, therefore, no waste takes place by reason of cutting it to avoid such parts.

I claim—

1. The process of producing a covering as an article of manufacture which consists of forming an integument of textile fabric on leather by cellular impregnation and union, the construction of the weave or mesh of the fabric being porous or intersticed to permit of impregnation or filling of leather and then splitting the leather by a cutting operation to form a complement one to the other in a composite uniform sheet of leather and textile having equivalent utility.

2. The process which consists of forming an integument of textile fabric on split leather by cellular impregnation and union of the split leather in the mesh or interstices of the textile fabric and then resplitting the leather by a cutting operation.

3. The process of producing a covering as an article of manufacture which consists of forming an integument of textile fabric on leather by embedding the leather to union with the fabric by cellular impregnation of their surfaces one or both surfaces coated with a flexible adhesive the construction or

design of the textile having porous or intersticed mesh on its contact or holding surface to anchor the leather in the body of the fabric and then splitting said covering by a cutting operation.

4. The process of producing a covering as an article of manufacture which consists of forming an integument of textile fabric on a flexible basic body by cellular impregnation of the basic body in the mesh of the fabric the design or construction of the fabric being formed with an irregularity to imitate or impart the appearance of leather, and then splitting said covering by a cutting operation to set and maintain said appearance.

5. The process which consists of leveling two or more sides or segments of leather of uneven substance by overlapping one portion upon another to distribute the substance to more even uniform thickness and to more regular surface area throughout, uniting the surfaces with a flexible coating body which will combine and compound with the leather and then shaving, splitting or acting upon the ridges or roughness to substantially level and smooth the sheet or sheets or both acting on the ridges to even them and then splitting.

6. The process which consists of forcing into split leather a filler which combines with and adds to its substance and firmness, applying thereto a textile fabric to unite therewith and then splitting the leather by a cutting operation substantially as described.

7. The process which consists of forming an homogeneous integument on a basic body of sheeting or leather by adding to its substance as a surface finish a constructive film of plastic coating body having yielding and pliable characteristics comparable to the leather and a textile web or sheeting of porous intersticed construction united one to the other by application of the plastic coating body thru the outer surface of the web or sheeting and combined to integral concrete consistency by pressing the leather or sheeting to intimate union by impregnation into the mesh of the porous textile.

8. The process which consists of joining a plurality of hides or segments of leather of uneven shape and substance by overlapping beveled edges one upon another to join and distribute the thicker portion upon the thin portion to thus level and distribute the substance, uniting the lapped surfaces with a flexible plastic coating body, and then pressing the combined sheet to form one larger more regular area of leather.

9. The process which consists in joining a plurality of hides or segments of leather of uneven shape and substance by overlapping beveled edges one upon another to join and distribute the thicker portion upon the

- thinner portion to thus level and distribute substance, uniting the lapped surfaces with a flexible plastic coating body, and forming therewith an integument of textile fabric by 5 homogeneous union with a plastic coating body, and then pressing the combined sheet to form a larger more regular area of leather.
10. The process which consists of joining a plurality of hides or skins of leather of uneven shape and substance by overlapping beveled edges one upon another to join and distribute a thicker portion upon a thinner portion to level and distribute the substance, 15 uniting the lapped surface with a flexible plastic coating body, then forming an integument of textile fabric on said leather by cellular impregnation and union of the leather in the meshes or interstices of the fabric, and then splitting the composite 20 sheet.
11. The process of producing a covering as an article of manufacture which consists of forming an integument of textile fabric on a flexible basic body by cellular impreg- 25 nation of the basic body in the mesh of the fabric, the design or construction of the fabric being formed with an irregularity to imitate or impart its appearance on the leather side of the fabric, and then splitting 30 said covering by a cutting operation to set and maintain such appearance.

FREDERICK W. MOORE.
